DEVICE FOR PUNCHING AND REENFORCING DOCUMENTS OR THE LIKE

Franz Lorenz, Dresden, Germany, assignor to Waldes & Ko., Dresden, Germany

Application March 29, 1934, Serial No. 717,937
In Germany April 7, 1933

5 Claims. (Cl. 93—1)

The present invention relates to devices for punching and reenforcing documents or the like in which on the downward movement of the hand lever the reenforcing strips unwound from spools or the like are fed forwards, cut off, pressed onto the paper and punched therewith. In such punching and reenforcing devices it has hitherto been usual to feed the reenforcing strip by means of a rack bar mechanism connected with the hand lever. This arrangement was not only very inconvenient but did not operate satisfactorily.

As distinguished therefrom in accordance with the invention the advance of the reenforcing strip is effected by feeding fingers or the like pivotally mounted and inclined to the direction of movement of the punches, the other ends of which fingers co-operate with the reenforcing strip guided on a support. In this manner a feeding mechanism is provided which in its mode of operation is very simple and permits uniform feeding of the reenforcing strips.

Suitably the support for the reenforcing strips is formed as a guide channel having its open side downwards, on the lower side of the vertically movable upper part of the punching apparatus, the feeding fingers formed as spring controlled single armed levers being movably arranged on the fixed base plate of the punching apparatus opposite the guide channel.

Moreover, there are suitably provided stops suitably adjustable with which the upper part of the punching apparatus contacts whereby the ends of the gripper fingers are moved away from the reenforcing strips and the feed of the reenforcing strip interrupted. As a result the advance of the reenforcing strips is conveniently interrupted at a quite definite position of the advancing finger so that the length of the strip fed forward is exactly determined.

In order to prevent the reenforcing strip from slipping back especially in the return movement of the feeding fingers resilient locking fingers are provided adjacent the guides for the reenforcing strips.

If reenforcing strips are employed the adhesive layer of which is not first brought into adhesive condition by warming or moistening or the like, i. e. if the strips are provided with a so-called permanent adhesive layer, then the strips are provided with raised or depressed portions as for example beaded edges, channeled edges or the like, produced by stamping or the like, and breaking up the smooth surfaces. As a result too great adhesion of the coiled reenforcing strips which

might produce difficulties in unwinding the reenforcing strips is prevented.

The invention is illustrated in the accompanying drawing in which

Fig. 1 shows a punching and reenforcing device in side elevation in which the feeding mechanism of the present invention is employed.

Fig. 2 is a view from the left of Fig. 1.

Figs. 3 to 5 show details to somewhat enlarged scale, while Figs. 6 and 7 show the reenforcing strip suitably employed in plan and in side elevation respectively.

Referring to the drawing, on the base plate *c* of the punching device are secured the two guide rods *d* on which the upper part *b* of the punching device can be moved downwards against the action of the helical springs *e*. The part *b* of the device carries the two punches *f* and the U-shaped guide channels *m* with their open sides downward and located at a suitable distance from one another, in which the reenforcing strips *p* being unwound from the spools *n* are guided, which strips are provided on the underside with permanent adhesive.

Adjacent each of the two guide channels *m* is arranged a feeding finger *i* formed as a lever, the pivots *s* of which are mounted on the lower portion *c* of the punching device. Adjacent each of the levers *i* is arranged a spring coiled on the pivot *s* which presses at one end against a pin *x* provided on the lower part *c* of the punching device and acting as an abutment and presses at the other end on the lower side of the lever *i*. Consequently the levers *i* with their ends which are formed as feed pawls tend to press against the reenforcing strips *p* lying in the channels *m*. Adjacent each of the guide channels *m* is arranged a spring *l* acting as a locking finger which with its end *y* presses from beneath on the reenforcing strips and thereby prevents return movement of the reenforcing strip *p*.

The modus operandi of the punching and reenforcing device is as follows:

The document laid on the base plate *c* and indicated by the dotted line *z* in Fig. 1 is pushed forward to the lower blade *h* secured to the base plate *c*. On depression of the hand lever *a* the upper part of the punching device and with it the two guide channels *m* are moved vertically downwards. The pointed ends of the levers *i* then enter the reenforcing strips and push the reenforcing strips in the direction of the arrow indicated in Fig. 4. Shortly before the opposing blades *g* on the part *b* of the punching device meet blades *h* the projections *k* provided on levers

i contact with the guide channels in the manner shown in Fig. 5. The pointed ends of the levers *i* are thus moved downward from the reenforcing strips and the advance of the strips thus interrupted. In the further downward movement of the upper part *b* of the device the portions *p'* of the strip projecting beyond the blades *g* are severed from the strips by the blades *g*, *h* and are pressed against the document by means of pads *r* of resilient material which are secured adjacent the punches *f* on the upper part *b* of the device. By compressing the pads *r* the punches which co-operate with the holes *w* provided in the lower part *c* of the device ensure the perforation together of the reenforcing strips *p'* and the document *z*.

If the hand lever and thus the upper part *b* of the device is released and allowed to move upwards again under the action of the springs *e* then the levers *i* move back under the action of the springs *q* into the position shown in Figs. 1 and 4. The springs *l* formed as locking fingers prevent any backward sliding movement of the reenforcing strips.

In the embodiment above described the projections *k* are made non-adjustable. They may, however, be formed of adjusting screws or the like so that the length of the strips of reenforcing material to be cut off may be varied or the feed regulated.

If as in the present embodiment reenforcing strips are used which are provided with so-called permanent adhesive then it is preferable to provide the surfaces of the reenforcing strips with raised portions or depressions in order to prevent strong adhesion together of the coils of the wound strip which would cause disturbances in operation. For example the strips *p* as shown in Figs. 6 and 7 may be provided with beaded edges *u*. These beaded edges can be formed by stamping or the like.

I claim:

1. In a device for punching and reenforcing materials or the like, the combination with a base, turnable spools for reenforcing strips mounted thereon and a vertically and linearly movable punch carrying frame cooperating with said base, of guide channels for said strips ar-

ranged on the bottom of said frame, rigid feeding means movably and resiliently supported on said base and projecting upwardly in a forwardly inclined position into said channels to press against said reenforcing strips, so that when said frame is moved downwardly said feeding means will feed said strips from said spools, and means on said feeding means adapted to be acted upon by said frame when reaching the punching position so as to disengage the feeding means from said strips.

2. In a device for punching and reenforcing materials, the combination with a base, turnable spools for reenforcing strips mounted thereon and a vertically linearly movable punch carrying frame cooperating with said base, of guide channels for said strips arranged at the bottom of said device, a pair of movably and resiliently supported rigid feed members on said base projecting upwardly in a forwardly inclined position into said channels, said members having gripping means to positively grip said strips so that when said frame is moved downwardly said gripping means will feed said strips from said spools, and means on said members adapted to be acted upon by said frame when reaching the punching position so as to disengage said gripping means from said strips.

3. In a device for punching and reenforcing materials as per claim 2, in which said channels are arranged in spaced relationship relative to one another, are U-shaped and adapted to engage the side edges of said strips with its lateral borders and expose the central part thereof through their open bottoms.

4. In a device for punching and reenforcing materials as per claim 2 in which the feed members are each in form of a rock lever influenced by a spring and pivoted to said base, each rock lever being formed at its upper end with a pointed gripping finger and at an intermediate point with an abutment, which when engaged by said frame while moving downwardly will release said gripping fingers from said strips.

5. In a device for punching and reenforcing materials as per claim 1, in which means are provided on said movable frame for locking said strips against retrograde movement.

FRANZ LORENZ.
